UNITED STATES PATENT OFFICE.

THÉOPHILE DUCOUSSO, OF PARIS, FRANCE.

ELECTRICAL APPARATUS FOR OPERATING RAILWAY SWITCHES AND SIGNALS.

SPECIFICATION forming part of Letters Patent No. 704,177, dated July 8, 1902.

Application filed September 22, 1898. Serial No. 691,597. (No model.)

To all whom it may concern:

Be it known that I, THÉOPHILE DUCOUSSO, a citizen of the Republic of France, residing in Paris, France, have invented certain new and useful Improvements in Electrical Apparatus for Operating Railway Switches and Signals, of which the following is a specification.

My invention relates to electrical apparatus for operating railway switches and signals, this apparatus being such that all the switches and signals of a station can be worked from a single center. The complete system includes a receiving or local apparatus situated near the switch or signal to be moved and connected thereto, or, in the case of several switches or signals to be operated by one lever at the central station, a corresponding number of similarly situated and connected local apparatuses, a series of operating or central-station apparatuses, one of which operates the local apparatus of each point or signal or group of points or signals, and a system of connections from said central station to said local apparatuses.

Figures 1 to 5, inclusive, are details of the local apparatus. Fig. 6 is a plan of a complete local apparatus, showing connections to the switch or signal and to the safety-bar. Fig. 7 is a section on the line $z z' z^2 z^3$, Fig. 6. Fig. 8 is an elevation of one complete central-station apparatus. Figs. 9 and 10 are details thereof. Figs. 11 and 12 are elevations of the central apparatus in different positions from that shown in Fig. 8 and showing the local apparatus connected thereto, the latter being diagrammatic for greater clearness. Fig. 13 is a diagram of the connections for the case in which one central-station apparatus operates several local apparatuses. The mechanical details of the parts are fully enough shown in Figs. 1 to 10, inclusive; and Fig. 14 is a diagram of a system of connections designed to secure safety in case of confusion or breakage or contact of the wires with the earth. Figs. 15 and 15^a are a plan and section, respectively, of the connections between the local apparatus and the switches, detector-bar, &c. Figs. 16 and 16^a are a side and edge elevation, respectively, of the interlocking mechanism at the central station.

In order to render the description clear, I shall first briefly describe the local apparatus, the line, and the central-station apparatus, 55 these three parts being afterward described in their different phases of operation in such combinations as insure safety.

Usually the switches and signals are arranged to move alternately, and often they 60 are furnished with systems of locking to prevent accidental change of position. The switches also are sometimes provided with detector-bars, preventing their movement while a car is over the bar. Such, briefly, are 65 the usual conditions which have to be kept in view in the course of the following description.

The local apparatus comprises an electric motor capable of revolving alternately in opposite directions—for instance, a dynamo having two fields wound in opposite directions communicating by a line-wire with the working station and an armature connected at one end with the two fields and at the other 70 end to a return-wire or earth. If at the central station one of the line-wires is connected to the one pole of a dynamo or battery the other pole of which is connected to the return-wire or earth, the motor will revolve in one direction, whereas the rotation will be reversed if the connections are made to the other wires. 80

Fig. 1 shows the arrangement for transmitting motion from the motor M to the switch through the rod A. The motor-shaft 85 g has on it a disk J, which has a finger driving a disk K, fixed on the shaft h of a worm V, which gears with a wheel R, loose on the axis O, said wheel R having a crank-pin and roller F, which works in a slot E e of a lever 90 D, fixed on a rocking shaft C, which has an arm B, jointed to the rod A. The slot has a straight part e and a part E, having for its sides circular arcs each concentric with the wheel R when the lever D is in its extreme 95 position corresponding to the symmetric arcs H H', which are separated by an arc I of about one hundred and eighty degrees. The sum of the three arcs H, I, and H' is the extent to which the wheel R revolves for a complete 100 stroke of the rod A. The arc I corresponds to the actual movement of the rod, the arcs H H' to the unlocking and locking. If the parts are in the positions shown in full lines in Fig.

1, a current is sent, causing the wheel R to turn in the direction of the arrow G. The crank F does not move the lever D while it traverses the arc H, because the side of the 5 slot is concentric with its rotation; but throughout the arc I the crank F, acting in the straight part of the slot, moves over the lever from its position 1 to position 2, moving the rod A through the stroke required for 10 working the switch or signal. While the crank continues its movement along the arc H' it acts on the concentric part of the slot, holding the lever in the dotted position. The current is automatically cut off a little before 15 the crank reaches the end of the slot E, as will be hereinafter explained. It is obvious that the two extreme positions of the lever D, as shown, respectively, in full and in dotted lines, are symmetrical. Consequently if 20 the current be sent by the other wire, causing the motor to revolve in the opposite direction, the rod A will be moved from position 2 to position 1 in the manner described. The locking of the switch or signal is effected by the 25 position of the crank F in the slot only when the movement of A has been completed in either direction. For applying the mechanism to a switch having a detector-bar I fix on the wheel R a cam L, Fig. 2, having two op- 30 posite parts of its periphery concentric, but of different radius. Against this cam bears a roller N of a lever P, fixed on a rocking shaft Q, the arm S of which is jointed to the rod T of the detector-bar. In a state of rest 35 the apparatus being in the one or the other of its normal positions, the roller N bears against the hollow of the cam L. The arc of the smaller circle beyond the part where the radius begins to lessen corresponds with H 40 in Fig. 1, so that while the crank-pin F traverses the arc H the roller N is moved away by the cam moving the arms P and S to the dotted position and the rod T from 1 to 2, raising the detector-bar if there be no car 45 over it; but if there be a car over the bar it cannot rise, the arms P and S cannot move, and the roller N prevents the cam L from moving, and thereby prevents the wheel R and the motor from revolving. The motor 50 is so constructed that it can sustain the current even when persistently locked. The cam L is so set that the switch or signal rod is not moved until the detector-bar is raised, and the bar is held raised during the movement 55 of the switch or signal rod, not descending until this movement is completed.

Figs. 3, 4, and 5 represent the snap-commutator which I employ for changing the connection of the motor to the line immediately 60 on the movements necessary for safety being completed by the motor. In a plane parallel to that of the wheel R, I arrange a rod U U', which can slide in guides u^2 u^3 and has its middle part U^2 larger, on which slides a 65 sleeve X. Two helical springs u u' abut against the guides u^2 u^3 and urge the sleeve X in opposite directions by washers x x' , free

to slide on U U', which has its one end jointed to an arm W of a rocking shaft W', which has another arm W^2 , jointed to a rod W^3 , 70 which is connected to a part moved by the switch or signal, so that the rod U U' moves with the switch or signal. The sleeve X carries a forked spring y insulated, this spring, as shown in Fig. 4, serving to connect the 75 contacts 40 and 42 or the contacts 41 and 43, which are fixed on an insulating-base, contacts 40 and 41 being connected to the two wires of the line and 42 and 43 to the two windings of the field of the motor. The sleeve 80 X does not move with the rod U U', but after it, as determined by the movement of the wheel R, which has two studs y' y^2 , meeting a lever Y, which is pivoted at Y^2 and has an end Y' , forming a stop for the sleeve X, being held in the position shown in Fig. 5 by a spring y^3 . Fig. 3 shows the commutator in one of its normal positions, corresponding to the position of the moving parts shown in Fig. 1. The current coming to the contact 90 40 passes by the fork y to the contact 42 and thence through the motor to earth. (See Fig. 6.) The wheel R moves in the direction of the arrow G, Fig. 1, and before the crank F has completed the arc H the stud y' sets free 95 the lever Y, the end Y' of which locks the sleeve X. While the crank F traverses the arc I, moving the switch or signal, the rod W^3 transmits the motion of the switch or signal to the rod U U' until the crank F has 100 completed the arc I. At this time the spring u' is compressed by the washer x' , but cannot act on the sleeve X, which is urged by the spring u , but is locked. When the crank F has traversed about half of the arc H', the 105 stud y^2 moves the lever Y, which releases the sleeve X, allowing it to be snapped by the spring u , moving the spring y from the contacts 40 and 42 to the contacts 41 and 43, thus preparing the connections for the opposite movements under control of the operating station. After the opening of the circuit the motor may slow down, continuing the motion of the wheel R and crank F through 110 the arc H'. The end Y' of the lever Y is kept 115 away from the sleeve X until by the movement opposite to that described the stud y' sets the arm Y free, which occurs at the beginning of the subsequent operation. This reverse operation is substantially the same 120 as that described; but it is the stud y' which releases the commutator. If the switch or signal should be accidentally displaced—as, for instance, by a forcing of the switch—there is fracture of some of the connections— 125 as, for instance, the rod A; but the rod W^3 nevertheless communicates to the rod U U' the movement corresponding with that of the switch or signal to its new position, and in the case shown in Fig. 3 the sleeve X, not being locked by Y' , also moves, shifting y from the contacts 40 42 to the contacts 41 43, which, as will be hereinafter described, informs the operator at the station of the accident. 130

The arrangement of the commutator as described, acted on by a rod W^3 , connected to the switch or signal, is the most effectual for safety; but in many cases—for example, for 5 switches in sidings—it is thought sufficient to control only the motor part of the apparatus. The end U of the rod $U' U$ may in that case be connected to a pin on an extension of the lever D , the rod W^3 and lever $W W^2$ being 10 dispensed with, as shown in the general plan, Fig. 6, and in the section, Fig. 7, on $z z' z^2 z^3$. As the same reference-letters are used to indicate like parts in all the views, Figs. 1 to 7, inclusive, it is unnecessary to further explain 15 Figs. 6 and 7.

Figs. 15 and 15^a show one mode of connecting my switch, signal, and safety-bars. The safety-bar T is connected to an arm f on a rock-shaft d , mounted in supports e . A bar c 20 is also connected to the rock-shaft d and in such position as to be depressed and held down while the wheel of the car is passing over the adjacent portion of the rail. The bars A and W^3 are connected to the switches 25 in any suitable way, as by articulated connection a' and b , respectively.

The line consists of two conducting-wires and a return which may be a third wire, or the rails, which serves for all the apparatus 30 of the same installation. The line may be underground, and so protected from accidents to which exposed wires are liable; but it may nevertheless be exposed, and I shall hereinafter state the accessory arrangements 35 to be employed, so that safety may not be compromised whatever be the condition of the line.

The central-station apparatus is shown in side view, Fig. 8, and transverse section, 40 Fig. 9. A frame 1 has fixed on it an axis 2, around which can turn the operating-levers 3 4 5, mounted behind the frame. A drawing-cam 6 is also pivoted on the axis 2 in front of the frame. A commutator 7 for three 45 contacts 8 9 10, and a reversing-switch, having two arms 11 and 12 for three contacts 13, 14, and 15, are mounted on a plate of marble or other insulating material 16, fixed on the frame. There is also fixed on the frame an 50 electromagnet 17, having its armature always on one of the cores on which it pivots when the magnet is excited. To the armature is fixed a lever 18, jointed to a bolt 19, which slides vertically in guides and which by its 55 weight keeps the armature away from the magnet except when it is excited. The upper end of the bolt does not project normally beyond the circular edge of the frame. On the rear side of the bolt there is a notch 20, 60 which when the bolt is raised comes in the path of a stud 21, projecting from the lever 3, and allows the lever to be moved. When the magnet 17 is excited, the lever 18 raises the bolt 19, which then projects beyond the edge 65 of the frame; but its notch allows the stud 21 to pass and the lever 3 to be moved forward. On the lever 3 is pivoted at 22 a double

pawl 23 24, right and left handed. Fig. 10 is a sectional plan on 22, showing the shape of the pawls and the free space between them. 70 The edge of the frame 1 forms an arc on which the pawls bear, and it has two notches 25 and 26. Also the cam 6 has two shoulders 27 and 28, projecting beyond the circular edge and in the paths of the respective pawls, and has 75 two notches 29 and 30, like 25 and 26 in shape, but not so far apart. The cam 6 has a crank-pin 31 connected to the reversing-switch by the rod 32, which insures the joint movement of the two parts and which is insulated from 80 the switch. The arm 5 of the lever is connected to the commutator by a rod 33, insulated as indicated in Fig. 9 and having a slotted hole which allows a little play in transmitting the movement of the lever to 85 the commutator. The arm 4 of the lever is connected by the rod 34 to the locking-bar 35, which may effect locking, according to any known system. The frame 1 is fixed on beams 36, to which are attached the other 90 operating mechanisms belonging to the station.

A suitable interlocking system for the bars 35 35' is shown in Figs. 16 and 16^a. The bar 35, connected to the lever 4 3, moves vertically in the frame V' as the lever is operated. 95 On the bar 35 is a notch X' . Two bars 35 and 35', operated by two levers 3 and 3', control distinct apparatus, switches, or signals. The two bars 35 and 35' are so controlled by 100 the angle-block Z on the horizontal sliding bar Y^3 that in the position shown the lever 3' is locked against movement. In order to move 3', it is necessary first to return 3 to its opposite position, in which the notch X' registers with the block Z . 105

The operation of the mechanism is shown in different phases in Figs. 8, 11, and 12, the two latter figures showing also, diagrammatically, the electrical connections with the 110 motor, consisting of the armature 37 and the two field-coils 38 and 39, their commutator being indicated diagrammatically by a pair of blades y and two contacts 42 and 43. The armature 37 is connected to earth or the common return, and the two field-coils 38 39 are connected to the line-wires by the commutator y , these wires meeting the blades 11 12 of the reversing-switch. The middle contact 14 of the switch connects to the electromagnet 115 17 and by it to the positive terminal of a battery or dynamo j , the other terminal of which connects to earth or the common return. The positive terminal has also a connection to the contact 9 of the commutator, 120 the arm 7 of which is connected to the contacts 13 and 15. Normally, as will be explained hereinafter, the position of the switch or signal is always in accord with the position of the operating-lever. Thus in Fig. 8 the 125 lever is to the right, like the receiving-commutator in Fig. 11. The movement of the lever to the opposite position, as shown in Fig. 12, takes place as follows: First the 130

locking-bar 35 must be free, and if so the lever can be at once moved to the position in Fig. 11 until the pawl 24 drops into the notch 25, indicating that the lever is free. At the same time the rod 33 is caused by the lever 3 to move the commutator 7 on to the contact 9, in which condition the lever is stopped by the stud 21 against the bolt 19. The lever cannot now be moved back, because the pawl 24 is in the notch 25, and the slight motion allowed is only equivalent to the play in the slot of 33, so that the commutator 7 is not altered. In the position Fig. 11 the current passes from 9 to 13 and by 11 to line, and by the commutator 7 and contacts 40 and 42 to the field-coil 38 and the armature 37, and thence to earth. The motor then acts as above described, moving the switches or the signal and breaking the contact 40 42 and making the contact 41 43. The current excites the magnet 17 and passes by 14 and 12 to line and by 41 43 to earth through the field-coil 39 and armature 37; but this current, owing to the resistance of the magnet-coil 17, is too weak to work the motor in the opposite direction, but it helps to stop it. The end of the lever 18 and the bolt 19 ascend, allowing the lever 3 to be moved over to the position in Fig. 12, the forward pawl having already passed the position of the bolt and the rear pawl being able to ride over the same. In the last part of its movement it moves the commutator-arm 7 on to the contact 10, and the pawl 23, having met the shoulder 28 of the cam, moves it, advancing the rod 32, and thus changing the reversing-switch 11 12, thus preparing the electric connections for the succeeding operation in the opposite direction, the line 11^a 40, which has just transmitted current to the motor, being ready for controlling the next operation of the switching mechanism and the line 12^a 41, which has just served for control, being ready for transmitting current to the motor for the next operation. The movement of the cam 6 from the position in Figs. 8 and 11 to that in Fig. 12 serves also to bring a full part of the cam 6 opposite the notch 25 in the frame and a hollow part thereof opposite 26, thus preparing the pawls 23 and 24 for the succeeding reverse movement. Thus the last part of the movement of the levers 3 4 5 is symmetrical with the first part and moves the locking-bar 35 as required. It will be seen from Figs. 8 and 12 that for the two extreme positions of the operating-lever all the movable parts occupy two symmetrical positions, so that the same phases as those described occur in their reverse movement. Assuming the apparatus to be for actuating switches and that the switch-operating mechanism being in the position shown in Fig. 12, the switches have been forced, still, as above described, the local commutator operates so that the contacts 41 43 are broken and 40 42 are closed. The current then passes through the coil of the magnet 17, the contact 14, the line 11^a 40, and

through the motor to earth. The magnet raises the bolt 19, which, as the forward pawl 24 meets the bolt, prevents the lever 3 being moved. Consequently the mechanism is locked with the controlling-circuit in its intermediate position and the switches must be rectified, restoring the circuits to one of the extreme positions before the lever can be worked. For such a case it may be useful to have an audible signal, such as an electric bell, arranged in shunt with the magnet 17, as shown, for example, at 72, Fig. 14, and sounding whenever the magnet is excited—that is to say, during each operation from the time when the control current is established until it is interrupted by the completion of the movement of the lever. Thus the electric bell would continue to sound when the corresponding switches are forced; but the same result would be obtained by inserting a bell in the wire leading from the battery to all the electromagnets of the station with a galvanoscope in shunt to each, so that there would be an audible signal for all the levers and a visible one for each. Owing to the mode of operation described, whenever the lever is moved to transmit current to the local apparatus it cannot be moved back to its extreme or normal position without first moving it quite over to the normal position corresponding to that of the local apparatus, which extreme movement, moreover, is possible only after reception of the control-current sent by the local apparatus itself after it has taken the required position. The effect of this control is that the operating-lever must always be in accord with the local apparatus. When an operating-lever works several switches or signals, the corresponding local motors are connected in parallel to the transmitting-line, so that they work simultaneously; but the passive resistances of these different apparatus may vary and cause a sensible difference in the time occupied in completing their movements. Consequently the control-current should not reach the operating-station to disengage the bolt there until all the apparatus have attained the required position.

For operating several sets of apparatus I adopt the arrangement shown in Fig. 13, in which three sets Z' Z² Z³ have their commutators, field-coils, and armatures denoted by the same numerals as in Figs. 11 and 12. Each apparatus has a second or control commutator like that shown in Fig. 4, acted on by the same sleeve and having its contacts on the same insulating-plate. For simplicity of description I have shown these commutators in Fig. 13 in the same form as the primary commutators, y being the springs, and 44, 45, 46, and 47 the contacts. In the most distant apparatus Z³ the contacts 44 and 45 are connected together and to earth and the contacts 46 and 47 are connected by insulated wires to the corresponding contacts 44 and 45 of Z², the contacts 46 and 47 of which are similarly connected to the contacts 44 and

45 of Z' , the contacts for which are connected to lines which are connected as follows to the main lines 11^a and 12^a : The lines 11^a and 12^a , starting from the blades of the reversing-
5 switch 11 12 of Fig. 12, go to two armatures 50 and 54 of electromagnets 51 and 48. The wire 11^a connects armature-lever 50 to the contact 49 and thence to the magnet 48 and the contacts 40 of all the apparatus. Similarly the wire 12^a passes by armature-lever 54 to contact 53, magnet 51, and the contacts 41 of all the apparatus. In fact, the circuit of each wire has its contact determined by a relay worked from the other wire and from said
10 contact passes through the coil of a relay, by which a contact is worked which controls the other wire, and thence to the motors. The armature 50 of the relay 51 has an angle-arm pulled by a spring to hold the armature
15 in contact with 49, said arm having its end arranged to become locked when the relay 51 is excited over the end of the armature 57 of a magnet 59, so that it cannot be unlocked until said magnet 59 attracts its armature.
20 The armature 50 cannot leave the magnet-pole 51 except on two conditions—viz., the armature 57 must be attracted and 50 must be no longer attracted. In like manner the armature 54 of the relay 48 is arranged to be locked
25 by the armature 56 of the magnet 58. The contact-stop 55 for the angle-arm of 54 is connected to the armature 56, also to one end of the coil of 58, the other end of which coil is connected to the control-contact 47 of the first apparatus
30 35 Z' . In like manner the contact-stop 52 is connected to the armature 57 and to the coil of 59, which is connected to the control-contact 46 of Z' . The coil of 58 cannot communicate with earth unless the contact 45 to 47 is established in all the apparatus $Z' Z^2 Z^3$, nor can the coil of 59 communicate with earth unless all the contacts 44 to 46 are established. The operation of this arrangement is as follows: Assuming the operator to send current by
40 wire 12^a , as described with reference to Figs. 8, 11, 12, this current will pass by 54 53 through relay 51, which it will excite, then to contact 41 and contact 43 of the field-coil 39 and the armature 37 of the three apparatus
45 50 working the motors; but, the armature 50 being attracted, contact with 49 is broken, while contact is established with 52, and thus the line-wire 11^a , which should serve for control, is cut off from the contacts 40 and put in communication through the coil of 59 with the control-contacts 44 to 46 of all the apparatus. When the movement of the apparatus is completed, the contact 41 to 43 is broken, as previously explained, cutting off current from the
55 60 motor, and the contact 40 to 42 is made. When this takes place in all the apparatus, the relay 51 becomes inactive, having current no longer; but simultaneously, as this is worked from the same sleeve, the control-commutator 65 acts, breaking the contacts 45 to 47 and making contacts 44 to 46. As soon as this occurs in all the apparatus the circuit for the con-

trol-current is closed, and this current causes the arm 57 to be attracted, setting free the arm of 50, which again makes contact with 49. At the operating-station this control-current produces also by the wire 11^a the effect described above—that is to say, the ascent of the bolt 19—allowing the lever to complete its stroke to a position corresponding with that of the apparatus. To sum up, local transmission-commutators 40 42 41 43 are branched in parallel on the circuit, while the commutators 44, 46, 45, and 47, which control the operation of the switch mechanism, are connected in series, and the two line-wires are commutated by the switches 49 50 52 and 53 54 55 on the lines for transmitting or for control, as required. The commutators 40 42 and 41 43 normally commutate the transmitting and motor circuit and act also for control-currents when the apparatus is in a wrong condition. The position shown in Fig. 13 for the local apparatus is in accord with that of the lever shown in Fig. 12. Should one of the local apparatus— Z^2 , for instance—be in wrong condition, then the contacts 45 47 will be broken and contact of 44 46 will be made, on the one hand, while contacts 41 43 will be broken and contacts 40 42 will be made, on the other hand. The contact 40 42 gives communication from the control-wire 11^a through the motor to earth, and this excites the magnet 17 at the station, which prevents the lever from being moved and calls the attention of the operator in the manner described. The relays and electromagnets 51, 59, 48, and 58 may be arranged in the casing of the first apparatus Z' or in a case near it; but it is to be noted that the two supplementary wires required for control extend only from the magnets to the last apparatus Z^3 —that is to say, within the limits of the group of apparatus that are simultaneously worked—while the line consists of the two wires 11^a and 12^a , extending from the operating-station to the group, with a common return-wire or earth. When the line-wires are exposed, they are subject to confusion, fracture, or contact with earth. In order that confusion or fracture of wires might not affect safety of traffic, I employ the arrangement shown in Fig. 14, which constitutes an automatic permanent control of the electric condition of the wires and apparatus. It is based on the use of two sets of differential currents, each controlling one wire of the line. When the line is in normal condition, the two branches of the circuit are in *equilibrio*. Any confusion or fracture of the line-wire destroys the equilibrium in one of the branches, which results in the raising of the bolt 19, and consequent stoppage of the operating-lever. For this purpose the receiving apparatus is provided with two resistances—say of two thousand ohms—connecting earth to the contacts 40 and 41, Fig. 14. Consequently the total resistance of each circuit from the operating-station is the same,

for the wire 12^a has the resistance of the line plus two thousand ohms and the wire 11^a has the resistance of the line plus the reduced resistance of the field-coils and the armature in parallel with two thousand ohms, or somewhat less than thirty ohms. At the operating station I place a relay 60, the coil of which consists of two equal wires wound oppositely. I also arrange a supplementary commutator 62, having two contacts 63 and 64, this being worked uniformly with 7 by an insulated connecting-rod. Also the electromagnet 17 is wound with two equal wires wound oppositely. The contacts 63 and 64 are connected together and to the battery, and the arm 62 is connected to the junction of the two relay-coils 60 through a resistance 61, which reduces the consumption. On the other hand, the battery is connected to the junction of the two coils of the magnet 17 through a resistance 67, which reduces the consumption. One of the relay-coils 60 is connected to the contacts 8 and 10 and through them to the line-wires. The other coil is connected to earth through a resistance 73 equal to that of the line-wire plus the reduced resistance previously described. One of the coils of the magnet 17 is connected to the contact 14 and through it to the line-wire. The other is connected to earth through a resistance 68 equal to that of the line plus two thousand ohms. From this arrangement it results that the parts being as shown in Fig. 14 a system of continuous currents of equal intensity is established in the two sets of coils of the relay 60 in opposite directions, so that the armature 65 is not attracted. A system of continuous currents of equal intensity and opposite direction is also established in the two coils of the magnet 17, and its armature is not attracted. Should there be fracture of the wire 12^a 41, there would be no current in the corresponding coil; but the other coil of 17 would be traversed by current and the armature 45 would be attracted. If instead of fracture of the wire 12^a 41 there were an earth contact or if there were contact of 41 to 43, resulting from derangement of the apparatus, the current in the one coil would be more intense than that in the other, causing excitement, attraction of the armature, and raising of the bolt. Similar consequences affect the relay 60—that is to say, if there be fracture, confusion, or earth contact of the wire 11^a 40 55 there would be a change of current in the corresponding coil, and consequent attraction of the armature 65; but in this case the movement of this armature makes a contact 65 66, which immediately connects to earth one of the coils of the magnet 17, which acts on the bolt. The commutator 62 is used for cutting the relay 60 off from the battery during the commutation resulting from the movement of the operating-lever. In other words, the differential electromagnet 17 controls the state of the controlling line-wire and translates into bolting of the lever the result of a defect in

the control-wire. The relay 60 controls the state of the operating line-wire, causing a bolting of the lever by the electromagnet 17 70 when the operating-wire is defective. In the two cases of bolting the lever as a direct or indirect consequence of defect in the line the attention of the operator is called by the continued sounding of the bell 72, which is in a 75 circuit including a battery and the contacts 70 71, worked by the armature of the magnet 17. This circuit may also comprise a galvanoscope, as mentioned above. This arrangement renders the working of an apparatus impossible when its line is defective and absolutely insures safety, and, further, it announces a defect immediately on its occurrence.

In order to apply the arrangement just described to a group of simultaneously-acting apparatus, I place the two thousand ohms resistance between earth on the one hand and the armatures 50 and 54, Fig. 13, on the other hand—that is to say, at the ends of the line-wires. Obviously in calculating the resistances 68 and 73 new elements occur—namely, the resistance of the relays 48 and 51—in reckoning the coils 68, and this same resistance added to the reduced resistance of the 95 motion in reckoning the coil 73.

My invention lends itself easily to interlocking arrangements depending on electric contacts. The locking-bar 35, Fig. 8, is in that case utilized to work the contacts, the arrangement of which may be according to any one of the many known systems; but it may be understood, for example, that two contacts adapted to the bar 35 might command the controlling and operating circuits of another 100 operating-lever which could not be moved unless the former lever were in a certain position, so that if the first lever is not in the required position it opens the operating-circuit and closes the controlling-circuit of the 105 second lever, and so prevents its movement.

Having thus described all parts of my system and its application to simple apparatus and also to groups of simultaneously-working apparatus with underground or exposed 115 wires combined with automatic and permanent control, I claim as my invention the arrangements described, reserving the right of application of the same to either switches or signals of both and of varying as required the 120 forms and sizes of the various parts, viz:

1. In mechanism for the electric working of railway-switches, a transmitting-commutator, a lever for working it, pawls on said lever acting in opposite directions, a current-controlled bolt, and means for projecting said bolt into the path of said pawls in case of accidental throwing of the switch.

2. In mechanism for the electric working of railway-switches, a transmitting-commutator, a lever for working it, pawls on said lever acting in opposite directions, in combination with a frame having notches adapted to receive said pawls, and means for closing said

notches to permit the passage of said pawls in the normal operation of the mechanism.

3. In mechanism for the electric working of railway switches and signals, a transmitting-commutator, a lever for working it, pawls on said lever acting in opposite directions, notches or stops on the frame adapted to receive said pawls, in combination with means for preventing engagement of the notches and pawls when moved in the forward direction and permitting engagement thereof in the opposite direction.

4. In mechanism for the electric working of railway-switches, a transmitting-commutator, a lever for working it, pawls on said lever acting in opposite directions, a frame having notches or stops adapted to receive said pawls, and a cam on said frame with two notches differing in position from those on the frame, the said cam adapted to disengage the pawl from the notch or stop for the movement of the lever forward, and to permit the pawl to engage the notch or stop for the back movement.

5. In mechanism for the electric working of railway-switches, a transmitting-commutator, a lever for working it, pawls on said lever acting in opposite directions, a frame having notches or stops thereon, a cam with two notches adapted to be brought into coincidence with the notches on the frame, and two shoulders on said cam in the path of said pawls whereby the cam is moved by the lever to the ends of its stroke.

6. In mechanism for the electric working of railway-switches, a transmitting-commutator, a lever, connections between said commutator and said lever whereby the movement of the latter controls the former, an electric bolt controlling the lever, two pawls on the lever, and a notched and shouldered cam adapted to be operated by said lever.

7. In mechanism for the electric working of railway-switches, a transmitting-commutator, a lever for working it, an electric bolt controlling the lever, two pawls on the lever, a notched and shouldered cam adapted to be operated by said lever, a reversing-switch adapted to be operated by said cam, and a motor attached to said railway-switches, in combination with a transmitting-circuit from said switch to said motor.

8. In mechanism for the electric working of railway-switches, a transmitting-commutator, a lever for working it, an electric bolt controlling the lever, two pawls on the lever, a notched and shouldered cam adapted to be operated by said lever, and a reversing-switch adapted to be operated by said cam, in combination with a transmitting-circuit and a circuit adapted to operate the electric bolt.

9. In mechanism for the electric working of railway-switches, a wheel, a crank-roller thereon, a slotted lever for locking and moving the switch, the wheel operating in said slot, a worm and electric motor for operating said wheel, and a commutator having two springs,

in combination with a rod attached to the moving part of the switch, and means connected to said rod whereby one or the other of the springs is strained by the movement of the switch.

10. In mechanism for the electric working of railway-switches, a wheel, a crank-roller thereon, a slotted lever, the roller operating in said slot, a worm and electric motor for operating said wheel, a commutator having two springs, and means for straining said springs by the movement of the switch, in combination with a releasing-lever and two studs on the wheel whereby the commutator is released when the switch is fully moved and locked.

11. In mechanism for the electric working of railway-switches, a wheel, a crank-roller thereon, a worm and electric motor for operating said wheel, a slotted lever operated by said roller and connected to said switch, a commutator having two springs, means for straining said springs by the movement of the switch, a releasing-lever for said springs, two studs on the wheel adapted to operate said lever, and a controlling apparatus and transmitting-circuit leading therefrom, the commutator being adapted to connect the motor and the transmitting-circuit.

12. In mechanism for the electric working of railway-switches, a wheel, a crank-roller thereon, a worm and an electric motor for operating said wheel, a slotted lever operated by said roller and connected to said switch, a commutator having two springs, means for straining said springs by the movement of the switch, a releasing-lever for said springs, two studs on the wheel adapted to operate said lever, a controlling apparatus, a transmitting-circuit leading therefrom, the commutator being adapted to connect the motor with said transmitting-circuit, a safety device, and means whereby the motor is connected to the transmitting-circuit during its action, and after its action is automatically put in circuit with said safety device.

13. In mechanism for the electric working of a group of simultaneously-acting switches, controlling apparatus, motors connected directly to said switches, transmitting-circuits connecting said controlling apparatus and said motors and comprising two wires, and a relay in each of said wires controlling the circuit of the other wire.

14. In mechanism for the electric working of a group of simultaneously-acting switches, central apparatus, local motors, line-wires connecting said apparatus, and a relay in each of the line-wires, in combination with a contact-breaker in each motor of the group, and an electromagnet in series with said contact-breakers, the electromagnet being so arranged as to lock the relay in one of its positions so that the relay is only released when all the contact-breakers in series close the circuit.

15. In mechanism for the electric working of railway-switches, a safety device and a

transmitting - circuit comprising two line-wires, in combination with two differential circuits, an electromagnet in one of said differential circuits and a relay in the other, 5 means for connecting said differential circuits to said line-wires and means connected with said electromagnet and said relay for controlling said safety device.

16. In mechanism for the electric working 10 of railway-switches, a safety device, a transmitting-circuit comprising two line-wires and two differential circuits, an electromagnet in one of said differential circuits and a relay in the other, means for connecting said differ-

15 ential circuits to said line-wires, means connected with said electromagnet for controlling said safety device, and means connected with said relay for controlling the current through said electromagnet, so that any break of equilibrium in the current of the 20 differential circuits works the safety device.

In testimony whereof I have signed this specification in the presence of two subscribing witnesses.

THÉOPHILE DUCOUSSO.
